Ernest O. Carlson, Rockford, Ill.

Application April 1, 1949, Serial No. 91,403

Term of patent 14 years

To all whom it may concern:

Be it known that I, Ernest O. Carlson, a citizen of the United States, residing at Rockford, in the county of Winnebago and State of Illinois, have invented a new, original, and ornamental Design for a Magazine Cabinet or the like, of which the following is a specification, reference being had to the accompanying drawing forming part thereof.

In the drawing:

cabinet or the like embodying my new design, and

Fig. 2 is a perspective view thereof with the parts in open position.

The sides opposite to those shown are plain.

I claim:

The ornamental design for a magazine cabinet or the like, substantially as shown and described.

ERNEST O. CARLSON.
